INVENTOR
John Karitzky
BY
Alonzo Johnson
ATTORNEY

UNITED STATES PATENT OFFICE.

JOHN KARITZKY, OF GARWOOD, NEW JERSEY, ASSIGNOR TO GARWOOD COMPANY, A CORPORATION OF NEW JERSEY.

TOGGLE.

1,374,924.

Specification of Letters Patent. Patented Apr. 19, 1921.

Application filed April 2, 1919. Serial No. 287,041.

To all whom it may concern:

Be it known that I, JOHN KARITZKY, a citizen of the United States, and residing at Garwood, in the county of Union and State of New Jersey, have invented certain new and useful Improvements in Toggles, of which the following is a specification, taken in connection with the accompanying drawing.

0 My invention relates to toggles and more particularly to a toggle in which the hinge member can be readily placed or changed by the mechanic. It further relates to such a toggle in which the hinge member is not 15 permanently secured to the toggle, as by riveting or other similar means.

My invention further relates to such a 20 toggle in which a head is formed preferably of spring material, which can be opened by the operator to insert the hinge member, or if a hinge member is already mounted in the head he can readily remove it in case he desires to substitute another form of hinge member.

25 My invention further relates to such a spring headed toggle which is preferably stamped out of sheet metal. At the same time that it is stamped, or subsequently, it may be provided with seats for the hinge 30 member and also, though not necessarily, with one or more stops. These stops are preferably formed by crimping over one or both of the free ends of the substantially V shaped head so that they will engage 35 with the bolt or other member and insure the proper alinement of the head with the bolt when it is inserted in the hole in the wall.

My invention further relates to certain 40 details of construction and combinations which will be more fully described in the specification and pointed out in the claims, and to a strong serviceable toggle which can be manufactured at minimum expense.

45 I have shown in the accompanying drawings different embodiments of my invention, but of course it is clearly understood that my invention is not to be confined to the particular forms shown by way of example 50 except as required by the scope of my claims.

In the accompanying drawings the same reference numerals refer to similar parts in the several figures.

55 Figure 1 is a perspective view of my tog-

gle in which the hinge member is an ordinary square screw-threaded nut;

Fig. 2 is a perspective view of the toggle head shown in Fig. 1 but provided with two stops formed by crimping over the free 60 ends of the head;

Fig. 3 is a detail view of one form of hinge member, that is used in Fig. 1;

Fig. 4 is a perspective view of one form 65 of my toggle in which the hinge member is a diamond shaped nut;

Fig. 5 is a plan view of a head similar to that in Fig. 4 but provided with two stops formed by bending inward the free ends of the head;

Fig. 6 is a detail plan view of the hinge 70 member used in Fig. 4;

Fig. 7 is a plan view of another form of hinge member which may be used, in which the trunnions are somewhat more pronounced than those in the form shown in Fig. 6;

Fig. 8 is a perspective view of a toggle head coöperating with a hinge member which is shown as a T headed bolt; and

Fig. 9 is a plan view of the T headed bolt shown in Fig. 8.

In the illustrated embodiments of my invention shown in the drawings 1 is a toggle head provided with arms 2 and 3 and 85 with seats 4, 4 to coöperate with any suitable form of hinge member. This hinge member may be the ordinary square nut 5, Fig. 3, or diamond shaped nut 6, Fig. 6, in which the ends 7, 7 are in effect trunnions, 90 or it may be a nut 8 in which the trunnions 9, 9, Fig. 7 are more pronounced, or it may be an ordinary T headed bolt 10, Fig. 9, or any other similar hinge member which is not permanently secured to the toggle head by 95 riveting or other similar means. These different forms of hinge members are interchangeable in my toggle head.

The hinge member 5, or any other suitable hinge member, may be placed in my toggle 100 head by pressing open the free ends 11, 11 of the arms 2 and 3. If the hinge member 5, 6 or 8, or any similar hinge member is used, the bolt 12 is screwed into the hinge member. To locate the toggle head in a 105 hole in a wall it is brought into alinement with the bolt 12; as soon as the ends 11, 11 escape the inner end of the wall (not shown) the end 13, being longer and heavier than the other end 14 of the head, will drop into 110

substantially the position shown in Fig. 1 when the bolt 12 may be screwed up to hold the work (not shown) to the wall.

Preferably, I make my toggle head out of sheet metal and at the same time that the toggle head is stamped I preferably, though not necessarily, provide it with the seats 4, 4 to coöperate with the hinge member, whatever the form of the hinge member 10 may be.

I also, preferably, though not necessarily, provide the free ends 11, 11 or one of them, with stops 15, 15 by bending over or crimping a portion of the end or ends. These 15 stops engage with the bolt 12 when the toggle head is brought into alinement with the bolt and prevent the head from swinging past the bolt, and keeps it in alinement with the bolt while it is being pushed into the 20 hole in the wall.

The toggle head may be given various configurations. I have shown for example in Fig. 4 a little different form of toggle head 16 in which any form of hinge member 25 may be used, as for example a diamond shape trunnion nut 6. I preferably, though not necessarily, provide this head with stops 17, 17, Fig. 5, which perform the same function as the stops 15, 15 in Fig. 2.

30 In Fig. 8 I have shown the toggle head 1 provided with a hinge member in the form of a T headed bolt 10; the head 18 coöper-

ates with the seats 4, 4 of the toggle head and is provided with a nut 19 to secure the work (not shown).

35

Having thus described this invention in connection with illustrative embodiments thereof to the details of which I do not desire to be limited, except as required by the scope of the appended claims, what is 40 claimed as new and what is desired to secure by Letters Patent is set forth in the appended claims.

What I claim is:

1. In a toggle bolt, the combination of a 45 spring head provided with an open end and seats for a hinge member, a hinge member freely and removably mounted on said seats, and a securing member to secure the spring head to a wall or other support and one or 50 more stops formed by bending one or both the free ends of the spring head.

2. In a toggle bolt the combination of a substantially V shaped head having its ends disconnected and said head being provided 55 with seats for a hinge member, a hinge member freely and removably mounted on said seats, and a securing member to secure the spring head to a wall or other support.

JOHN KARITZKY.
